Primary Examiner — Anhdao Doan

(74) Attorney, Agent, or Firm — Buchanan Ingersoll & Rooney PC

(57) **CLAIM**

The ornamental design for a gel distribution module, as shown and described.

DESCRIPTION

FIG. 1 is a top view of the gel distribution module showing my new design;

FIG. 2 is a bottom view thereof;

FIG. 3 is a right side view thereof;

FIG. 4 is a left side view thereof;

FIG. 5 is a rear side view thereof;

FIG. 6 is a front view thereof; and,

FIG. 7 is a top and front perspective view thereof.

1 Claim, 5 Drawing Sheets(56)
